UNITED STATES PATENT OFFICE.

THOMAS M. JACKSON, OF CLARKSBURG, WEST VIRGINIA.

SURVEYOR'S SELF-READING LEVEL-ROD.

SPECIFICATION forming part of Letters Patent No. 254,980, dated March 14, 1882.

Application filed November 10, 1881. (No model.)

To all whom it may concern:

Be it known that I, THOMAS M. JACKSON, of Clarksburg, in the county of Harrison and State of West Virginia, have invented certain new and useful Improvements in Surveyors' Self-Reading Level-Rods; and I do hereby declare that the following is a full, clear, and exact description thereof, reference being had to the accompanying drawings, and to the letters of reference marked thereon, which form part of this specification, in which—

Figure 1 is a front view of a section of my improved staff, showing part of its graduated face, full size. Fig. 2 is a cross-section. Fig. 15 3 shows two sections of the face of the staff, more fully exemplifying my mode of graduating the same. Fig. 4 is a front view. Fig. 5 is an edge view of the full rod, showing the back swell.

20 This invention relates to improvements in rods or staffs which are used by engineers for leveling.

My invention consists in a novel construction of the leveling-rod, whereby it is stiffened, preventing it from warping, and the graduation-marks on one of its surfaces are guarded from injury by the bruising of the straight-edge of the rod, as will be hereinafter fully explained.

I prefer to construct the rod A of clear, well-30 seasoned white pine, sixteen feet long. It is straight on the left or graduated edge a, but increases in width from the lower end of the right-hand edge, c', to the center, and diminishes from this point to its top, as shown in Fig.

35 4. The graduated face is flat and perfectly smooth, but the back swells from the ends to the center similar to the right-hand edge, c'. This swelling of the rod from ends to center stiffens it, preserves it straight, and admits of 40 its use as a measuring-pole as well as a leveling-rod. The bottom of rod A is shod with metal, so as to inclose its end and prevent undue wear and battering when subjected to rough usage, and the front of the straight edge 45 is beveled, as shown in Figs. 1, 2, and 3, for the purpose of guarding the graduated edge a and preventing it from being bruised or the graduating-marks marred or obliterated. I prefer to paint the rod white, and on this 50 white background I paint the graduations or divisions, and cover the same with a suitable

transparent varnish. The rod is marked off in feet, sixteen in all, beginning at the bottom and numbering upward, each foot-figure being two-tenths of a foot high and marked distinctly with a bright red color. The exact foot-marks are at the top of each foot-figure, and indicated by a black transverse line extending across the rod. Each foot is divided into ten equal parts, and each even tenth is numbered by the even figures 2 4 6 8, their tops indicating the exact mark and the intermediate spaces indicating odd tenths. Again, each tenth is subdivided into ten equal parts by alternate black and white bars or stripes, varying in length, so that the eye can readily detect them. It will be seen by reference to Figs. 1 and 3 that the bars are longer at the center, and that the exact center of each tenth is marked by an arrow-head. Each one of the black and white bars 70 is one-hundredth of a foot wide, and the top of each bar indicates the even number of hundredths—2 4 6 8—while the bottoms of the bars or tops of the spaces give the odd numbers—viz., 1 3 5 7 9. It will thus be seen that 75 the division-marks read to one-hundredth of a foot, making it very accurate by the graduations themselves, and avoiding the guessing at fractions, as these, to the extent named, are actually read directly on the rod.

It will be observed that all of the blank tenths are odd, and all blank hundredths are odd, so that in reading the rod through the instrument the black spaces indicate the even tenths and the white spaces the odd tenths, 85 thus rendering the calculation exceedingly simple and the taking of the observation very clear. Each figure should be read at its exact top—that is, in looking through the instrument at the rod the correct reading is that lying immediately below the horizontal cross-hair. To illustrate this, suppose, for example, that the cross-hair of the instrument cuts the rod exactly at the bottom of the black (tenth) figure 6. Thus the reading would be five feet and five-tenths, always reading at the top of the figure. If it were at the top of (tenth) figure 6, it would read five feet six-tenths. If at the bottom of figure 4, it would read five feet three-tenths. If at c, Fig. 1 of the drawings, it would read 100 five feet six-tenths and three-hundredths. If at d, it would read five feet six-tenths and six-

five *six*

hundredths. The arrow-head between *c* and *d* would indicate five feet six-tenths and five-hundredths. The center of the red figure 6 gives five feet and nine-tenths, and the top of this figure gives exactly six feet. In this manner the scale or graduate marks can be quickly read off by the engineer looking through the instrument, the rodman's duty being simply to plant the rod wherever directed.

10 In constructing my leveling rod I prefer to observe the following proportions, although I do not confine myself strictly thereto: the width of the rod at its bottom two inches, at the center two inches and one-quarter, and at 15 the top one inch and three-quarters. The thickness will be one inch at the bottom, one and one-quarter inch at the middle, and seven-eighths of an inch at the top. Such a rod not only serves for leveling, but it is useful for 20 cross-sectioning and measuring both by rod-distances and stadia.

Having thus fully described my invention, what I claim as new, and desire to secure by Letters Patent, is—

25 1. The graduated leveling-rod formed of one piece, having one straight edge, one flat grad-

uated face, a swelled edge, and a swelled back, for the purpose described.

2. A leveling-rod to be used upright, having graduated marks transversely across its face, 30 indicating feet and tenths of a foot, the feet being designated by figures two-tenths of a foot in length, and the even tenths by figures only one-tenth of a foot in length, the long and short bars of different colors indicating hundredths of a foot, and arrow-heads applied to the longest bars indicating the exact center of each tenth of a foot, the whole being arranged as shown and described.

3. A leveling-rod having a beveled straight 40 edge, *a*, the graduating-marks extended only to the inner angle of the said bevel, the swelled back, and swelled right-hand edge, substantially as described.

In testimony that I claim the foregoing as 45 my own I affix my signature in presence of two witnesses.

THOMAS MOORE JACKSON.
